CUTTER CHAIN

Warren Noble, Michigan City, Ind., assignor to
 Sullivan Machinery Company, a corporation of
 Massachusetts

Application November 27, 1934, Serial No. 755,013

22 Claims. (Cl. 262—33)

This invention relates to cutter chains, and more particularly to improvements in a cutter chain especially designed to use with a cutter bar of a coal mining machine.

5 An object of this invention is to provide an improved mining machine cutter chain. Another object is to provide an improved cutter chain having improved cutter bit positioning and holding means. Yet another object is to provide 10 an improved cutter bit whereby, due to its particular design, relatively long life is insured, the bit being of such shape as to possess better heat distribution qualities. A still further object is to provide an improved mounting means for a cutter bit of the above character whereby the 15 bit may be supported in different angularly related positions with respect to the bit block. Yet another object is to provide an improved reversible bit block structure with which the improved bit holding and adjusting means is associated, 20 whereby, by turning the holding and adjusting means end for end with respect to the bit block, the cutter chain may operate in either direction. These and other objects and advantages of the 25 improved cutter chain will, however, hereinafter more fully appear as the description proceeds.

In the accompanying drawings there are shown for purposes of illustration two forms which the invention may assume in practice.

30 In these drawings,—

Fig. 1 is a side elevational view of one illustrative form of the improved cutter chain structure.

Fig. 2 is an end elevational view of the cutter chain structure shown in Fig. 1.

35 Fig. 3 is a view in longitudinal section taken substantially on line 3—3 of Fig. 2.

Fig. 4 is a cross sectional view taken on line 4—4 of Fig. 1.

Fig. 5 is a perspective view of the bit clamp 40 element.

Fig. 6 is a perspective view of the bit positioning and supporting element.

Fig. 7 is a perspective view of the improved cutter bit.

45 Fig. 8 is a view similar to Fig. 1 showing a modified form of construction.

Fig. 9 is an end elevational view of the cutter chain structure shown in Fig. 8.

Fig. 10 is a view in longitudinal section taken 50 substantially on line 10—10 of Fig. 9.

Fig. 11 is a detail sectional view taken on line 11—11 of Fig. 8.

Figs. 12 and 13 are side and end elevational views respectively, of the bit positioning and 55 supporting element.

Figs. 14 and 15 are side and end elevational views respectively, of the bit clamping element.

In the illustrative embodiment of the invention disclosed in Figs. 1 to 7, inclusive, there is shown a bit block 1, a series of which are adapted to be pivotally connected together in end to end relation by suitable strap links or otherwise to form an endless cutter chain in a well known manner. Formed integral with the bit block 1 is a projecting boss or lug 2 having a longitudinal bore 3 formed with its interior periphery serrated at 4. Mounted in this bore 3 is the cylindrical shank 5 of a bit positioning and supporting element 6, the exterior periphery of the shank 5 being formed with longitudinal teeth 15 engageable with the serrations formed in the walls of the bore 3 for locking the shank against angular displacement within the lug bore. As illustrated, the shank 5 is axially bored at 7 to receive the bolt-like body portion 8 of a bit clamping element 9. The rear end of this bolt portion is threaded at 10 to receive a tightening nut 11 engageable with the rear surface of the lug 2. The bolt portion 8 is preferably annularly grooved at 12 to receive a snap ring 13 for preventing inadvertent release of the nut 11 from the bolt.

The improved cutter bit 14, as shown in Figs. 3 and 7, is of the so-called detachable type and preferably in the form of a stamping pressed to the desired shape and hardened to attain relatively great wearing qualities, and is, in this instance, preferably of V-shaped cross section having its end cutting faces 15 lying in the plane sides of a right-angled dihedral angle to provide cutting portions at the opposite bit ends. The end portions 16 of the bit are inwardly bent, as shown in Fig. 3, to obtain relatively great strength at the cutting point. It will thus be seen that the cutter bit is reversible so that when one cutting point becomes dull, the bit may be turned end for end relative to its holding means, thereby to present a fresh cutting point to the work. The bit is of a relatively inexpensive design, and when both cutting points become dull, it may be discarded and replaced by a new bit.

40 The bit positioning and supporting element 6 is provided with a portion 17 projecting forwardly and outwardly from its shank 5 and of tapering shape to provide ample support for the rearward portion of the bit body and formed in its front face with an inclined or tapering socket 18 of V-shape, within which the outer contour of the bit body is adapted to fit. Formed on the clamping element 9 is a forward and outward projection 19 of V-shaped cross section 50

shaped to fit the inner contour of the bit, the projection 19 engaging the intermediate portion of the forward surface of the bit body and cooperating with the portion 17 of the supporting element to form an interfitting clamp in which the bit is firmly held. The elements 17 and 19 of the bit holding and supporting means are of such shape as to provide ample clearance for the cutting portion of the bit. These elements, in certain instances, may be composed of copper or metals having similar heat conducting characteristics for preventing concentration of heat at the cutting point of the bit, resulting in longer bit life. By the provision of the serrations within the longitudinal bore 3 and the teeth cut on the shank of the element 6, it is possible to adjust the bit supporting structure into different angularly related positions with respect to the bit block lug, as shown in Fig. 2, thereby to obtain "lacing" of the bits of the chain without the use of a large number of bit blocks of different shape, it being noted that in this improved construction but a single bit block pattern is needed to provide for all necessary bit positions. It will be evident, moreover, that the cutter bit may be firmly held in position on the bit block.

In the modified form of construction shown in Figs. 8 to 15, inclusive, there is shown a bit block 20 having longitudinally spaced lugs 21 and 22 30 having aligned bores 23 and 24 respectively, these bores having their inner peripheries serrated at 25. Arranged in the space between these two projecting lugs is a bit supporting and positioning element 26 having a forwardly projecting shank 27 extending within the bore 24 in the lug 22 and having external teeth 28 engageable with the bore serrations for locking the shank 27 against angular movement within the bit block lug. Engageable with the forward surface of the rear lug 21 is an adjusting nut 29 having a circular projection 30 projecting within the lugged bore 23 and having a smooth exterior surface of a diameter just permitting it to pass into the serrated bore. Threadedly engaging the nut 29 is a bolt portion 31 of a bit clamping element 32. As shown in Fig. 11, the member 26 has lateral projections 33, 33 engaging ledges 34, 34 formed on the member 32 for preventing angular outward tilting movement of the member 32 with respect to the member 26 and bit block lug. Clamped between the members 26 and 32 is a cutter bit 35 of the same general design as that shown in Fig. 7, although in this particular instance of somewhat greater length. The member 32 has a bit supporting portion 37 tapering forwardly and outwardly and having a V-shaped recess 38 in its forward face shaped to fit the outer contour of the bit block, while the rearward inclined portion of the member 26 is of V-shape to fit the inner contour of the bit body, and these elements 26 and 32 cooperate to form an interfitting clamp within which the bit body is firmly gripped. As in the form of the invention above described, the projecting elements of the bit holding and clamping elements may be composed of copper or similar metal to attain better heat distribution qualities.

The cutter bit may be supported in different angularly related positions with respect to the bit block simply by rotating the nut 29 to move it back (to the right in Fig. 10) along the bolt portion 31 removing the element 32 and bit from the bit block, withdrawing the toothed shank from engagement with the serrated bore 24 of the front lug and turning the element 26 into a different angularly related position with respect

to the bit block. The toothed shank of the element 26 is then again inserted within the serrated bore 24, the bit placed in position between the assembled elements 26 and 32, as shown in Fig. 10, and the nut 29 thereafter rotated to bring the cylindrical projection 30 thereof within the rear lug bore 23 and to clamp the parts firmly together. It will thus be seen that the cutter bit may be firmly held in position on the bit block and may be adjusted, as in the form of the invention above described, into different angularly related positions with respect to the bit block to obtain "lacing" of the bits.

It will be noted that in both forms of the invention the bit positioning and holding structure may be turned end for end with respect to the bit block, thereby to attain ready reversal of the cutter bits in the chain, the bit blocks being symmetrical in form so that the bit holding structure may be supported in either position. Also in either form of the invention the cutter bit may have its walls longitudinally corrugated to obtain great rigidity in a bit of relatively thin structure, and further the gripping walls of the cooperating clamping elements may be roughened or serrated to provide a better grip on the bit. In certain instances the V-slot of the bit may be filled with copper to further improve the heat distribution of the bit. These and other uses and advantages of the improved cutter chain will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. A cutter bit having a straight body of V-shaped cross section and having at its opposite ends inwardly bent cutting portions.
2. A cutter bit having a straight body and having its opposite ends inwardly bent to form oppositely inclined end cutting faces providing cutting points at the same side of the bit body.
3. A cutter bit having a straight body of V-shaped cross section, and oppositely inclined end cutting faces providing cutting points at the same side of the bit body, the bit body at the bit points being inwardly bent.
4. In a cutter chain, a series of articulated bit blocks each bit block having a longitudinal bore, the inner periphery of said bore being serrated, a bit positioning and supporting element having a toothed shank insertible in said bore, and a bit holding element cooperating with said positioning and supporting element and engaging the bit for securing the bit in cutting position on said positioning and supporting element, the toothed shanks being insertible in different positions in different bit block bores to obtain lacing of the bits.
5. In a cutter chain, a series of articulated bit blocks each bit block having a longitudinal bore, the inner periphery of said bore being serrated, a bit positioning and supporting element having a toothed shank insertible in said bore, and a cooperating bit clamping element for securing said bit positioning and supporting element in said bore and engaging the bit for clamping the bit in cutting position on said positioning and supporting element, the toothed shanks being

insertible in different positions in different bit block bores to obtain lacing of the bits.

6. In a cutter chain, a bit block having a longitudinal bore, the inner periphery of said bore being serrated, a bit positioning and supporting element having a toothed shank insertible in said bore, and a cooperating bit clamping element for securing said bit positioning and supporting element in said bore, said toothed shank having an axial bore and said clamping element having a bolt-like portion projecting through said axial bore.

15 7. In a cutter chain, a bit block having a longitudinal bore, the inner periphery of said bore being serrated, a bit positioning and supporting element having a toothed shank insertible in said bore, and a cooperating bit clamping element for securing said bit positioning and supporting element in said bore, said toothed shank having an axial bore and said clamping element having a bolt-like portion projecting through said axial bore, said bolt-like portion being threaded to receive a tightening nut.

25 8. In a cutter chain, a bit block having longitudinally spaced lugs, said lugs having aligned bores, the internal peripheries of said bores being serrated, a bit positioning and supporting element having a toothed shank insertible within the bore in the front lug, a bit clamping element, and an adjusting element cooperating with said clamping element and having a portion projecting within the bore in the rear lug.

35 9. In a cutter chain, a bit block having longitudinally spaced lugs, said lugs having aligned bores, a double-ended reversible cutter bit, and a bit holding and positioning means supported within the lug bores and providing an obliquely inclined socket for receiving the cutter bit for supporting the bit in an inclined position with its active cutting end projecting outwardly and forwardly from the bit block a substantial distance in advance of its inactive cutting end, said bit holding and positioning means adjustable relative to the bit block to move said cutter bit 40 into different angularly related cutting positions, an element of said bit holding and positioning means having a locating portion engageable with locating portions formed within the inner periphery of the bore of the front lug, said bit reversible end for end with respect to said holding and positioning means in any of aforesaid angularly related cutting positions.

45

50

10. In a cutter chain, a chain block having a bit lug, said lug having a bore, a cutter bit holder including a support element having a bit receiving socket and a tubular shank, said shank receivable in said lug bore, and a bit clamping element having a bolt-like body portion extending through said tubular shank and an integral forwardly projecting portion shaped to fit the forward surface of a cutter bit.

11. In a cutter bit and bit holder, a cutter bit having a body of V-shaped cross section, a bit positioning and holding element having a V-shaped socket for receiving the bit body and a tubular shank, and a bit clamping element for clamping the bit within said socket having a bolt-like portion projecting through said tubular shank and an integral V-shaped projection adapted to fit within the bit body.

70 ed to fit within the bit block.

12. In a cutter chain, a bit block having a bore, a cutter bit holder for holding a cutter bit in position on said block including a support element having a bit receiving socket and a tubular shank, 75 insertible in said bit block bore, and a bit clamp-

ing element having a bolt-like body portion extending through said tubular shank, and an integral forwardly projecting portion shaped to engage a cutter bit in said socket.

13. In a cutter chain, a bit block having a bore, a cutter bit holder for holding a cutter bit in position on said block including a support element having a bit receiving socket and a tubular shank insertible in said bit block bore, and a bit clamping element having a bolt-like body portion extending through said tubular shank, and an integral forwardly projecting portion shaped to engage a cutter bit in said socket, said bolt-like portion having a threaded end projecting through said tubular shank and a clamping nut threaded thereon. 5 10 15 20

14. In a cutter bit and holder, a cutter bit having a body of V-shaped cross section, a bit positioning and holding element having a V-shaped socket for receiving the bit body, and an integral tubular shank, a bit clamping element for clamping the bit within said socket having a bolt-like portion projecting through said tubular shank, and an integral V-shaped projection adapted to fit within the bit body, said bolt-like portion having a threaded end projecting through said tubular shank and a clamping nut threaded thereon. 25

15. In a cutter chain, a bit block having a lateral lug formed with a longitudinal bore, a bit holder having a tubular shank received in said lug bore, and a bit clamp having a body portion projecting through said tubular shank.

16. In a cutter chain, a bit block having a lateral lug formed with a longitudinal bore, a bit holder having a tubular shank received in said lug bore, a bit clamp having a body portion projecting through said tubular shank, and means co-operating with said clamp body portion and said lug for clamping said bit holder in the lug bore. 35

17. In a cutter chain, a series of articulated bit blocks each bit block having a longitudinal bore, the inner periphery of said bore formed with locking surfaces, and means for positioning and supporting the cutter bits in different positions on different blocks including bit clamps for supporting the bits independently of bit engagement with the blocks, said clamps each having a positioning and supporting element provided with a shank insertible in a block bore and having locking surfaces engaging the block bore locking surfaces for locking the shanks against rotation in the bore, the shanks of said elements insertible in different positions in different bit block bores to obtain lacing of the bits on the chain. 40 45 50

18. In a cutter chain, a series of articulated bit blocks each bit block having a longitudinal bore, the inner periphery of said bore formed with locking surfaces, and means for positioning and supporting the cutter bits in different positions on different blocks including bit clamps for supporting the bits independently of bit engagement with the blocks, said clamps each having a positioning and supporting element provided with a shank insertible in a block bore and having locking surfaces engaging the block bore locking surfaces for locking the shanks against rotation in the bore, the shanks of said elements insertible in different positions in different bit block bores to obtain lacing of the bits on the chain, said clamps also including a bit clamping element co-operating with said positioning and supporting element for securing said positioning and supporting element in a block bore.

19. A bit clamp comprising a clamping element having a bolt-like body portion and an integral 75

forwardly projecting portion V-shaped to fit the forward surface of a cutter of V-shaped cross section, and a cooperating clamp element having a tubular shank for receiving said bolt-like body portion and having a V-shaped slot for receiving the rearward surface of the cutter bit.

20. In a cutter bit holder, a support element having a bit receiving socket of V-shape for receiving the V-shaped body of a cutter bit, and a tubular shank, and a bit clamping element having a bolt-like body portion extending through said tubular shank and an integral forwardly projecting V-shaped portion shaped to engage the cutter bit in said socket.

21. In a cutter bit holder, a support element having a bit receiving socket of V-shape for receiving the V-shaped body of a cutter bit, and a tubular shank, and a bit clamping element hav-

ing a bolt-like body portion extending through said tubular shank and an integral forwardly projecting portion V-shaped to engage the cutter bit in said socket, said bolt-like body portion having a threaded end projecting through said tubular shank and a clamping nut threaded thereon.

22. In a cutter chain, a chain block having a bit lug, said lug having a socket, a bit positioning and holding element having a tubular shank receivable in said lug socket, and a bit clamp having a portion receivable and movable axially in said tubular shank, and means for moving said clamp portion axially relative to said tubular shank to clamp a cutter bit in cutting position on said bit positioning and holding element.

WARREN NOBLE.
